UNITED STATES PATENT OFFICE.

JOHN R. BOSTWICK, OF CLIFTON SPRINGS, NEW YORK.

SANITARY MILK-CAN.

1,022,819.

Specification of Letters Patent.

Patented Apr. 9, 1912.

Application filed February 23, 1910. Serial No. 545,284.

To all whom it may concern:

Be it known that I, JOHN R. BOSTWICK, of Clifton Springs, in the county of Ontario and State of New York, have invented a new and useful Improvement in Sanitary Milk-Cans, which improvement is fully set forth in the following specification and shown in the accompanying drawings.

This invention relates to certain new and useful improvements in receptacles designed primarily for use as milk cans, but, as is evident, adapted for other purposes.

It has for its objects among others to provide what I term a sanitary milk can, so constructed that the entire interior surface of the can below the rest for the cover is practically continuous and smooth, being free of creases, grooves or open joints, thus rendering it capable of being conveniently, readily and thoroughly washed and avoiding places which would tend to hold little remnants of milk which would sour therein. It has for a further object to provide a simple and efficient protecting jacket which will serve not only to resist transmission of external heat through the walls of the can to its contents, but which will also strengthen the can and enable it to better withstand the rough handling which it is sure to get while in transmission in the baggage cars on the railroad and at other times.

I form the upper end of the can in a novel manner for coöperation with the cover so as to prevent upward slopping of the milk from passing outward around the cover, so that should the milk splash upward, the comparatively smaller diameter of the body at the top will direct the splashes of the milk past the joint between the cover and the contiguous portion of the body and into the hollow member of the cover, thus breaking the force of the splashes so that none of the liquid can pass outward between the cover and the contiguous surface of the cylindrical portion of the upper end of the can.

Other objects and advantages of the invention will hereinafter appear and the novel features thereof will be particularly pointed out in the appended claim.

The invention is clearly illustrated in the accompanying drawings, which, with the numerals of reference marked thereon, form a part of this specification, and in which—

Figure 1 is a side elevation of the can with

parts broken away and other parts in central vertical section. Fig. 2, drawn to a larger scale, shows the upper portions of the can with a slight modification in the form of the upper end of the main body portion. Fig. 60 60 Fig. 3 is a plan of the can viewed from above, a part of the cover being broken away. Fig. 4 is a side elevation of the cover detached, parts being broken away and shown in diametrical section on the dotted line *a* in Fig. 65 65 3. Fig. 5 shows more fully the construction at the bottom of the can, parts being broken away and in vertical axial section. Fig. 6 is a detail side view of an embodiment of the invention in which the handles are secured to a band which fits snugly the body of the can. 70

Like numerals of reference indicate like parts throughout the several views.

Referring to the drawings, 1 designates 75 the bottom of the can which is shown as saucer-shaped having at its upper edge an annular outwardly extending flange 2, as seen clearly in Figs. 1 and 5. It is formed preferably at its edge 3 practically on the 80 arc of a circle, meeting the lower contiguous portion 4 of the body 5 of the can as in a continuous line, seen best in Fig. 5, so there is left no roughness of the inner surface where the said bottom and the lower end of 85 the body of the can meet. The joint at this point may be closed by solder or otherwise so that no milk or other fluid can enter the joint.

The flange 2 of the bottom 1 extends over 90 and rests upon the upper edge of the bottom ring or foot 6, which latter element is common in cans of this general character, and the body portion 5 of the can has a circular shoulder or extension outward, as shown at 95 7, see particularly Fig. 5, which rests upon the flange 2 of said bottom, and the lower end of the body portion is then extended to form an annular portion or skirt 8, which extends downward over the outer edge of 100 the flange 2 and snugly embraces the bottom ring or foot 6, to which latter it is secured in any suitable manner, as by rivets or other suitable fastenings 9. By this means, the bottom proper of the can is held rigidly in 105 place and is protected against contact with the ground or other substance upon which the can may be supported. Furthermore, the joint between the curved edge 3 and the adjacent lower contiguous portion 4 of the 110

body 5 is held against separation so as to avoid opening of the joint at this point.

In constructing the can, I provide a jacket which serves the double function of protecting the body of the can proper during rough handling while in transmission or in use and at the same time resist the transmission of external heat through the walls of the can to the milk or other contents.

10. In Fig. 1 I have shown one form of protecting jacket, as at 10. This extends from near the bottom of the can to a point at or about the midheight thereof, its upper end being secured to the body 5 by a ring of solder or the like, as at 11. This jacket is also conical, but of a slightly less sharp inclination than the body 5, it touching the body at its upper end but leaving a gradually increasing space 12 which is of comparatively considerable width at its lower end, as seen clearly in Fig. 1. The lower end of this jacket extends downward and beyond the top edge of the skirt 8 and is there firmly secured in any suitable manner, as seen at 13, as by solder or otherwise. Within the conical space 12, just referred to, I place a sheet or sheets or layer or layers of asbestos 14, or some other suitable substance that will resist the transmission of external heat through the walls of the can to the milk. This is preferably arranged as seen in Fig. 1, so as to leave an air space upon both sides thereof to increase the heat resisting qualities. This jacket may be corrugated, as at 15 in Fig. 1. These corrugations, while not necessarily always present, serve to strengthen the jacket, as well as to materially protect the same during the rough handling that such a can is liable to receive in use.

15. In Fig. 6 I have shown another form of jacket as at 16. This is comparatively short, the upper end being secured to the body 5 by a ring of solder or the like, as seen at 17, and the lower end being likewise secured to the body by a ring of solder or the like, as seen at 18. If desired this form of jacket also may be corrugated, as seen at 19. Also the corrugations may extend horizontally or vertically or at an inclination, or both, as may be found most expedient. In this form the jacket fits snugly to the body of the can and the interposed heat resisting material is not employed.

20. Handles 20 are employed, as seen in the different views, said handles being secured to the jackets of whichever form may be employed, the handles being disposed at a point substantially near the midheight of the can for convenience in handling. These handles are riveted to the jacket without riveting through the body of the can. The jackets may be of any suitable height, as may be required to protect the can against becoming indented or jammed, as its differ-

ent uses may require. By this means, rivet heads on the inside of the vessel or can are avoided.

A can constructed as above described has the following advantages. It can be easily cleaned and kept in a sanitary condition as it is constructed so as to avoid all turns, bend, or sharp angles on the inside and all of the inner surface is fully exposed to view, while the body 5 of such a shape or form 75 that the sides of the same will not come in contact with the sides of similar vessels in handling or shipping and, by this means, the can is not liable to become jammed or dented and thus uneven surfaces on the inside are prevented, which also adds to the ease of cleansing the interior of the can.

21 designates the cover.

22 is a cylindrical band at the upper end of the body portion. This ring or band is 85 made rigid with the body 5 by a tapered ring of solder or the like 23, as seen in said Fig. 1. This band is formed with a circular horizontal crease or outwardly extending recess 24, as seen in Fig. 1, into which the outer edge of the outwardly extending flange 25 at the upper end of the body 5 projects and into which it is rigidly soldered, leaving a horizontal flange or circular shoulder 26 for receiving the bottom edge 90 of the cover, as is clearly shown in Fig. 1.

The cover 21 is constructed of parts, as shown in Figs. 1 and 4. These comprise the two hollow or saucer-shaped members 27 and 28 disposed in opposite relation, that is turned bottom to bottom, as seen clearly in said views, and the lower member being cylindrical. Around the lower cylindrical part 28 is placed a second cylindrical part 29, which latter is designed to telescope directly within the band 22 to tightly close the can, as seen in Fig. 1. At its upper end, the cylindrical part 29 is turned outwardly to form an outwardly projecting horizontal flange 30, around the outer edge of which the extreme outer edge of the upper conical member 27 of the cover is folded and clamped, as shown clearly at 31 in Fig. 4. The lower edge of the part 29 is turned upward slightly to inclose the lower edge of the part 28, this folded or rounded portion 32 resting directly upon the shoulder 26 of the upper end of the body, as seen clearly in Fig. 1. The cover is formed with an upwardly projecting handle 33, as shown in Figs. 1, 2, 3 and 4, which is formed with a downwardly projecting horizontal stiffening rib 34, as seen best in Figs. 1 and 4.

The upper edge of the band 22 is rolled outward around a wire 35, as shown clearly 12 in Figs. 1, 2 and 4.

In the form shown in Fig. 2, the upper end of the body portion 5, instead of being turned outward to form the horizontal flange described in connection with Figs. 1 13

and 4, is coiled around a wire 36, as shown, the coil being outward to meet the inner surface of the cylindrical band 22. This forms a ring or internal recess 37 for the lower edge 32 of the cover, answering the same purpose as the shoulder 26 in the form shown in Fig. 1. In this form, the band 22 is plain and not provided with a groove or recess, as is the form shown in Fig. 1 at 24. 10 The result is substantially the same. The object of this shoulder or recess is to prevent the upward slopping of milk from passing outward around the cover, the internal diameter of the lower portion of the cover being greater than the diameter of the mouth of the body portion 5, as shown clearly in Fig. 1, so that if the milk splashes upward, the comparatively smaller diameter of the body at the top will direct the 20 splashes of milk past the joint between the cover and the contiguous shoulder, 26 or 37, as the case may be, and into the hollow of the lower member 28 of the cover. This breaks the force of the splashes and none 25 of the milk can pass upward and outward between the cover and the contiguous surface of the cylindrical band 22.

Modifications in details may be resorted to without departing from the spirit of the invention or sacrificing any of its advantages. 30

What is claimed as new is:—

A milk can comprising a cone shaped body having an outwardly turned upper end, a band formed from sheet material and 35 rigidly secured to and about the upper end of the body, the inner walls of said band being parallel, and a closure having a cylindrical portion tightly fitting the inner wall of the band from the upper edge of the latter to the upper edge of the can body, the lowermost portion of the cover resting upon the upper edge of the can body, and the cover being provided with a downwardly opening chamber entirely above the cone 40 shaped body. 45

In witness whereof, I have hereunto set my hand this 17th day of February, 1910, in the presence of two subscribing witnesses.

JOHN R. BOSTWICK.
